UNITED STATES PATENT OFFICE

JACK SCHWEIZER, OF RYE, NEW YORK, ASSIGNOR TO THE SCHWARZENBACH HUBER COMPANY, OF NEW YORK, N. Y., A CORPORATION OF NEW JERSEY

DESIGN FOR A TEXTILE FABRIC OR THE LIKE

Application filed November 8, 1932. Serial No. 45,809. Term of patent 3½ years.

To all whom it may concern:

Be it known that I, JACK SCHWEIZER, a citizen of Switzerland, residing at Rye, county of Westchester and State of New York, have invented a new, original, and ornamental Design for a Textile Fabric or the like, of which the following is a specification, reference being had to the accompanying drawing, forming part thereof.

The figure is a surface view of a piece of textile fabric or the like, showing the design. The area within the dot and dash line shows

one complete unit of the design. The repeats are arranged in vertical rows and adjacent vertical rows are one half a complete unit offset so that the angle of the complete unit indicated by letter A corresponds with angle B of one of the repeats in an adjacent vertical row.

I claim:

The ornamental design for a textile fabric or the like, as shown and described.

JACK SCHWEIZER.
